UNITED STATES PATENT OFFICE

ROY H. CUNNINGHAM, OF FAIRFIELD, CONNECTICUT, ASSIGNOR TO THE BRYANT ELECTRIC COMPANY, OF BRIDGEPORT, CONNECTICUT, A CORPORATION OF CONNECTICUT

ESCUTCHEON

Application filed May 7, 1929. Serial No. 361,099.

This invention has to do with escutcheons for doors and its object is to make it possible to have an escutcheon of molded material such for example as a phenolic condensation product or a substance containing such a product. An escutcheon of that material is desirable in that it is easily shaped and is pleasing in appearance, but a difficulty inheres in its use where a knob is used. 5 The spindle of a door knob is ordinarily somewhat loosely supported and therefore is capable of a limited movement sidewise. It has been found that attempts to use a molded escutcheon have been unsuccessful 10 because the knob or its spindle in moving sidewise engages the molded material and breaks it.

In the accompanying sheet of drawings, in which Figures 1 and 2 are respectively an 20 elevation and a central sectional view, I have shown an escutcheon of molded material which is entirely practicable and avoids the likelihood of the knob's causing a fracture in the molded material.

25 The escutcheon is made up principally of molded material. The molded face portion 10 is given any desired surface configuration in the molding operation and has a shallow recess 11 in its back, i. e. in the side 30 adapted to rest against the door sash. A metal plate 12 rests in the recess and lies flush with the surface of the back. There is an annular boss 13 formed in the molded material at the rim of the opening 14 into 35 which the shank of the knob extends and through which the knob spindle passes. In the re-enforcing plate 12, there is an opening 15 in register with the opening 14 in the molded material, but of smaller size.

40 The escutcheon is held to the door by screws passing through the eyelets 16 which serve to hold the two parts of the escutcheon together. A key hole 17 may be provided when desired and the idea of a smaller hole 45 in the plate than in the molded material may be applied to it as well if it is found that there is any tendency to break the molded material in manipulating the key. Ordinarily it is not necessary to do so.

50 Neither normal movement of the knob

sidewise nor movement coupled with considerable force, as when the door sticks and is lifted by lifting the knob, causes fracture of the escutcheon since the opening in the molded material is large enough so that 55 with the maximum amount of play of the spindle, the part of the knob unit adjacent the molded material will not press against it.

I claim—

1. An escutcheon comprising a portion of 60 molded material and a re-enforcing member, the two having registering openings, the opening in the re-enforcing member being the smaller, for the purpose described.

2. An escutcheon comprising a face portion 65 of molded material having an opening for a knob spindle, and a re-enforcing plate on the back thereof, said plate having an opening in register with and smaller than the opening in the face portion, for the purpose described.

3. An escutcheon comprising a face portion 70 of molded material having an opening therethrough for a knob spindle, and a shallow recess in its back, together with a re-enforcing plate resting in said recess, said plate having an opening in register with and smaller than the opening in the molded material, for the purpose described.

4. An escutcheon comprising a face portion 75 of molded material having an opening therethrough and an annular boss at the rim of the hole, together with a re-enforcing plate having a smaller opening in register with the opening in the face portion, for 80 the purpose described.

In testimony whereof I have signed my name to this specification.

ROY H. CUNNINGHAM.
